(57) **CLAIM**

The ornamental design for a cartridge assembly, as shown and described.

DESCRIPTION

FIG. 1 is a perspective view of a cartridge assembly;

FIG. 2 is an exploded view thereof;

FIG. 3 is a top view thereof;

FIG. 4 is a left side view thereof;

FIG. 5 is a right side view thereof;

FIG. 6 is a front view thereof;

FIG. 7 is a rear view thereof; and,

FIG. 8 is a bottom view thereof.

The portion of the design shown in FIG. 2 in broken lines forms no part of the claimed design.
